UNITED STATES PATENT OFFICE.

FRED T. BAUM AND CLARENCE G. NORRIS, OF MARION, INDIANA.

BRICKMAKING MACHINE.

Application filed July 22, 1927. Serial No. 207,752.

This invention relates to a mold for forming a particular type of concrete block.

An object of the invention is the provision of a mold for forming a hollow concrete block having one surface faced to simulate a brick formation and in which the blocks will present an odd number of bricks on one row with an even number disposed on top of the odd number of bricks.

10 Another object of the invention is the provision of a mold having hinged doors of step formation and a face plate cooperating with the doors and a plurality of cores movable through a back plate.

15 A further object of the invention is the provision of a mold for forming a concrete block of a particular formation and in which end doors are hinged to a frame which is swingable to a vertical position for cooperation with a horizontally disposed face plate.

20 A core adapted to be moved in a horizontal plane into the mold and guided by a back plate through which the cores are inserted.

This invention will be best understood 25 from a consideration of the following detailed description in view of the accompanying drawings forming a part of the specification; nevertheless it is to be understood that the invention is not confined to the disclosure, 30 being susceptible of such changes and modifications which shall define no material departure from the salient features of the invention as expressed in the appended claim.

In the drawings:-

35 Figure 1 is a view in perspective of a molding machine constructed in accordance with the principles of our invention.

Figure 2 is an end view showing the mold in open position with the concrete block reversed,

40 Figure 3 is a view in perspective of a concrete block which is formed by my molding machine,

Figure 4 is a side view of my molding machine,

45 Figure 5 is a plan view of the same,

Figure 6 is a transverse vertical section taken along the line 6—6 of Fig. 8,

Figure 7 is a longitudinal vertical section, 50 showing the mold in closed and operative position, and

Figure 8 is a longitudinal vertical section of the molding machine showing the same in an inoperative position.

55 Referring more particularly to the drawings 10 designates a table having side bars

11 and 12 supported by legs 13 formed of angle iron construction. A plate 14 is secured to the front legs 13 and has a horizontally disposed flange 15 carrying adjusting bolts 16 threaded into perforations in said flange.

60 A pair of arms 17 are pivotally mounted at 18 on the table and are provided with horizontal extension 19. A face plate 20 when in an operative position is located in a horizontal plane and secured to the arms 17 and is adapted to rest upon the side bars 11 and 12 of the table. The arms 17 are adapted to rest upon the upper ends of the adjustable 65 bolts 16.

65 A pair of push rods 21 are slidably mounted in the passage 22 in the extensions 19 and a spring 23 embracing a rod 21 engages the head 24 of said rod and also the 70 outer face of the face plate 20, said rod passing through a perforation in the plate at the lower end thereof. The inner end of each rod 21 is expanded as shown at 25, and seated within a similarly shaped socket 26 at the 75 so inner surface of the face plate to prevent said push rod from being accidentally discharged from the face plate. A pair of bolts 27 secure the face plate to the extensions 19 and also provide means for adjusting the face 80 plate relative to the extensions 19.

85 The push rods are operated by an actuating lever 28 secured to a rod 29 which is rotatably mounted in the side bars 11 and 12. A handle 30 provides means for actuating said lever for forcing the said lever into engagement with the head 24 of the push rod to slide a pallet 31 horizontally along the arms 17 and away from the face plate 20 after the block has been completed. It will be noted 90 that the levers 28 are mounted in spaced relation on the rod 29 so that when one of the levers is actuated the other lever will be operated simultaneously so that both levers act upon the push rods 21 to provide a uniform 95 horizontal movement of the pallet 31.

100 The inner surface of the face plate is provided with a rib 35 and pockets 36 with intersecting or transverse ribs 37 and 38 to provide for the appearance of the brick formation on the face of the block when said block has been completed. The periphery of the 105 face plate is provided with ribs 39 which cooperate with ribs 35, 37 and 38 to form the pockets 36. These ribs provide for the depressions 41 and 42 of the outer face of the block while the curved edges of the pockets 110

cause a slight beveling as shown at 43 and 44, of the block 45 so that when the blocks are fitted together in a building the wall of the building will give the appearance of having been built of bricks.

A pair of doors generally designated by the numerals 46 and 47 are hinged at 48 on a pintle 49 carried by extensions of the arms 17. Each door consists of a pair of vertical plates 50 and 51 connected together by a horizontal plate 52 to provide a step formation and in which the plate 52 is approximately half the width of a brick section 53 of the block 45. The plate 50 is cut away at 54 and adjacent the hinge 48 to neatly receive an end of the pallet 31. Each of the doors has pivotally connected to the outer face of the plate 51, a catch 55 which engages over an edge of a back plate 56 for locking the back plate to the doors 46 and 47.

The back plate 56 is provided with a plurality of passages 57 through which are adapted to be moved a plurality of hollow cores 58. The back plate is reinforced by cleats 59 and straps 60 are secured to said bars and hinged at 61 to the side bars 11 and 12 of the table. The back plate may be swung away from the block and likewise the mold when said block is set.

The cores 58 are connected together for simultaneous movement and a U-shaped reciprocating rod 70 is secured to one of the cores and is adapted to be oscillated in guides on brackets 71 secured to the side bars 11 and 12. A link 72 is pivotally connected with the reciprocating rod 70 and with a yoke 73 hingedly connected at 74 to the side bars 11 and 12. An operating handle 75 is rigid with the yoke so that when the same is oscillated the rod 70 will be reciprocated in a horizontal plane for moving the cores 58 in the same horizontal plane.

A mold 80 is mounted on the opposite end of the table 10 for the purpose of producing a block which is rectangular in cross section and which has one face formed to simulate a plurality of bricks cemented together.

The operation of our device is as follows:

The mold section is swung to the position shown in Fig. 7 with the face plate 20 supported by the side bars 11 and 12 of the table and the arms 17 disposed in a vertical position with the pallet 31 likewise located

in vertical position and in engagement with the arms 17. The back plate is swung on its pivot and has its lower edge seated upon the inner face adjacent the inner end of the face plate. The handle 75 is actuated causing the rod 70 to be moved inwardly in a horizontal plane and positioning the cores 58 above the face plate and with the ends of the cores in engagement with the pallet 31. The doors 46 and 47 are then moved to the proper position and the concrete is filled into the mold and around the cores 58 and sufficiently tamped to prevent air pockets. The latches 55 are moved into position so that they will engage over the vertically disposed ends of the back plate 56. Since the mold has been set the handle 75 is moved outwardly until the pin 81 engages the guide 71 and limits the outer movement of the cores 58. The back plate 56 is then moved away from the mold and the arms 17 and swung to the horizontal position where they will rest upon the bolts 16. Either one of the levers 28 is rocked forcing the push bolts 21 inwardly and moving the pallet 31 away from the face plate so that the lock may be readily removed, after the latches 55 have been released from the back plate 56.

The doors 46 and 47 and the back plate 56 close on top of a face plate 20, so that the lower edge of the door is aligned with the rib 39 and over the continuation of the rib with one edge of the face plate. The back plate 56 is also aligned over the top of this rib and the edge of the pallet 31 on which the block rests also rests on the edge of this plate so that the doors, back plate and pallet are all in alignment with the inside edge of the rib 39 which is disposed around the entire outer edge of the face plate.

We claim:

A mold comprising a face plate, arms projecting laterally from the face plate, a pallet supported upon said face plate, doors hingedly mounted on the arms, a back plate and a core carried by the back plate adapted to be positioned over the face plate, push rods slidably mounted in the face plate and adapted to engage an edge of the pallet, and means for reciprocating the push rods for forcing the pallet away from the face plate.

CLARENCE G. NORRIS.

FRED T. BAUM.
